REFRIGERATING APPARATUS AND METHOD

Lawrence A. Philipp, Detroit, Mich., assignor, by
mesne assignments, to Nash-Kelvinator Corporation,
Detroit, Mich., a corporation of Maryland

Application November 23, 1932, Serial No. 644,061

7 Claims. (Cl. 62—126)

This invention relates to refrigerating apparatus, and more particularly to multiple temperature refrigerating apparatus.

One of the objects of my invention is to provide an improved multiple temperature refrigerating system wherein different temperatures are maintained in different evaporators, by controlling the heat transfer characteristics of some or all of the refrigerant evaporators.

10 Another object of my invention is to operate the aforesaid system with substantially equal pressures in the different evaporators and to maintain a temperature differential between the evaporators by retarding the flow of refrigerant through some of said evaporators.

Another object of my invention is to arrange for maintaining different temperatures in a refrigerating system by selectively controlling the heat transfer characteristics of one or all of the refrigerant evaporators in said system.

20 Another object of my invention is to provide an improved method for maintaining a temperature differential between a number of the different refrigerant evaporators of the refrigerating system.

25 Another object of my invention is to provide a refrigerating system of the type in which liquid and gaseous refrigerants are circulated through the different evaporators at substantially equal pressures, and to arrange for retarding to a predetermined amount the flow of refrigerant through some of said evaporators to vary the heat transfer characteristics of some of said evaporators to thereby maintain a predetermined temperature differential between the said evaporators.

30 Another object is to arrange for injected expanded refrigerant from a common source into each of the aforesaid evaporators to insure substantially uniform temperatures throughout the various parts of each evaporator without affecting the temperature differential between the various evaporators.

Another object of my invention is to provide 35 an improved refrigerating system in which a temperature differential is maintained between a number of refrigerant evaporators by the use of primary and secondary refrigerants and a simplified system of controls therefor.

40 Further objects and advantages of the present invention will be apparent from the following description, reference being had to the accompanying drawings, wherein a preferred form of the present invention is clearly shown.

45 55 In the drawings:

Fig. 1 is a view shown partly diagrammatically and partly in cross section of a refrigerating apparatus embodying features of my invention;

Fig. 2 is a view taken along the line 2—2 of Fig. 1;

Fig. 3 is a view taken along the line 3—3 of Fig. 1;

Fig. 4 is an enlarged fragmentary view shown in cross section of a valve mechanism used for controlling the flow of refrigerant in the apparatus shown in Fig. 1;

Fig. 5 is a view in cross section of a modified form of refrigerating apparatus embodying features of my invention;

Fig. 6 is a view taken along the line 6—6 of Fig. 5; and

Fig. 7 is a diagrammatic representation of a modified form of refrigerating apparatus embodying features of my invention.

Mechanical refrigerating systems wherein different temperatures are maintained generally comprise an intermittently operated refrigerant condensing unit and a number of different refrigerant evaporators operatively associated with the condensing unit, the number of refrigerant evaporators depending upon the number of compartments to be refrigerated. Systems of this type require the provision of some means for maintaining different temperatures in the different evaporators.

The systems heretofore used customarily included pressure reducing valves at the inlet of each evaporator and pressure responsive valves at the outlet of some or all of the evaporators. The pressure responsive valves prevented the withdrawal of refrigerant vapor and heat from the different evaporators until predetermined pressures existed therein. By this arrangement a temperature differential is maintained between the different evaporators by maintaining different pressures in the evaporators.

Valves of the type hereinbefore mentioned are expensive to manufacture and the pressure responsive valves, which are usually of the snap-acted type, are very likely to become out of proper adjustment or misadjusted by someone unfamiliar with the operation of the system.

Another type of system in which different temperatures can be maintained is the so-called slop-over system, which includes a number of different evaporators placed at different heights so that refrigerant in excess of a certain amount flows into an evaporator located on a lower level. To obtain different pressures in different evapo-

rators in systems of this type, it has been proposed to throttle the vapor lines of some of the evaporators to maintain different pressures, and consequently, different temperatures in the different evaporators. Systems of this type are unsuitable for installation in ice cream cabinets wherein it is very desirable to have the various evaporators positioned on the same horizontal plane. Furthermore, there is lacking the selectivity of temperatures in the different evaporators, it being necessary in such systems to maintain a lower temperature in the uppermost evaporator, for the reason that higher pressures in the evaporators located at lower levels prevents the flow of liquid refrigerant from the uppermost evaporator to said other evaporators.

In accordance with my invention, I arrange a plurality of refrigerant evaporators in open communication with each other, and I also arrange to retard the flow of refrigerant through some of said evaporators by restricting the outlet of some of said evaporators to thus decrease the circulation of refrigerant through some of said evaporators to thereby vary the heat transfer characteristics of the different evaporators. By this arrangement, I maintain a predetermined temperature differential between some or all of the different evaporators without the use of pressure reducing valves for each evaporator and without the use of pressure responsive valves.

Referring now to the drawings for a detailed description of the invention, the numeral 20 designates, in general, a cabinet of the type suitable for storing ice creams, frozen packaged goods, and the like, to be kept at low temperatures. The cabinet is constructed of insulated walls 24 which cooperate to form a compartment 26. Within the compartment is disposed a refrigerant low side 28 of a refrigerating system. A refrigerant high side or condensing element 30 of the system is operatively associated with the low side.

The refrigerant low side comprises, in general, a header 34 adapted to contain a quantity of liquid refrigerant. The header is preferably of tubular formation and is provided on one end thereof with a valve plate 36 clamped between a cover plate 38 and an end ring 39, which is preferably welded to the tubular wall of the header. Depending from the lowermost portion of the header is a stand pipe or refrigerant accumulator 41 which is in open communication with the interior of the header. Refrigerant expansion coils, evaporators or conduits 43, 44 and 45, are connected to one end thereof with the lower end of the accumulator by means of a refrigerant supply conduit 50 which is in open communication with each of the expansion coils 43, 44 and 45 and with the interior of the refrigerant accumulator. Each of the refrigerant evaporators 43, 44 and 45 is connected on their upper ends to the header above the level of liquid refrigerant therein by means of vapor conduit 52 and extension conduits 54, 55 and 56, of the expansion coils 43, 44 and 45, respectively. Suitable float valve mechanism is provided within the header for the purpose of maintaining a substantially constant level of liquid refrigerant therein. The float valve mechanism includes a float 60 and a valve 62 which cooperate with valve seat 63 to control the passage of liquid refrigerant from the high pressure side of the condensing element to the low pressure side or expansion conduits. The header 34 and accumulator 41 are supported by an enclosure 65, which is constructed preferably of thin 75 sheet metal.

The expansion coils 43, 44 and 45 are wound around and in good thermal contact with tanks or sleeve members 67, 68 and 69, respectively. The tanks or sleeve members are arranged to accommodate one or more open top food containers 5 72. The cabinet is provided with removable covers or lids 73 for ready access to the containers.

The refrigerant condensing element 30 comprises, in general, a compressor 75, condenser 77, motor 78 for operating the compressor, and a liquid refrigerant receiver 80. The compressor withdraws gaseous refrigerant from the cooling or evaporating elements through a vapor conduit 82, compresses the gaseous refrigerant and delivers it to the condenser wherein it is liquefied 15 and from which it is delivered to the liquid refrigerant receiver. Liquid refrigerant is delivered to the various evaporators through a supply conduit 84. An automatic switch 85 is provided for controlling the operation of the motor in response 20 to changes in pressure in the vapor conduit in the well known manner.

Suitable connections 87 and 88 are provided in the cover plate to which the conduits 82 and 84 are connected, respectively. Liquid refrigerant passes from the supply conduit 84 to the connection 88 and when the float valve is opened the liquid refrigerant passes through the orificed valve seat 63 into passage 90 which communicates with a conduit 92. Liquid refrigerant passes through 30 the conduit 92 whence it is injected into the inlet end of the supply conduit 50 by means of an injector or nozzle 95 in a manner about to be described.

During periods when the float valve is open, 35 liquid refrigerant passes through conduit 92 and injector 95 into conduit 50. Since the accumulator 41 is in open communication with the header 34 and the conduit 50 is in open communication with the accumulator, the level of 40 liquid refrigerant within the expansion conduits 43, 44 and 45 will normally be the same as in the header 34. When refrigerant is being injected into the supply conduit 50, a portion thereof will flow through the outlets or upper ends of the expansion conduits 43, 44 and 45 and into the header 34 until the float rises sufficiently to close the float valve 62.

From the foregoing, it will be apparent that the large volume of liquid refrigerant in the header and accumulator will cause evaporated 50 refrigerant in the expansion conduit to pass through the outlet ends of the expansion conduits and into the gas space in the header due to the resistance offered by said large body of liquid. Under some circumstances, it has been found that the evaporation of refrigerant has 55 been so great in the expansion conduits as to pick up liquid refrigerant and deliver it to the header, whence it descends into the accumulator 60 to be re-circulated.

In order to promote and to initiate the ebullition and to promote the circulation of liquid refrigerant through the expansion conduits, the injector has been provided. This prevents the 65 superheating of liquid refrigerant in the expansion conduits and tends to maintain uniform temperatures throughout the various parts of each of the expansion conduits or evaporators. The injector is formed by restricting the outlet 70 end 98 of the conduit 92. The restricted end 98 is disposed part way into a fitting 100 to which the supply conduit 50 is connected. A recessed casing 102 is provided as a mounting and covering for the injector. The casing 102 on its up- 75

per part is secured to the accumulator, preferably by welding. The injector is adapted to inject expanded refrigerant into the supply conduit 50. During periods when the float valve 62 is open, the refrigerant leaving the high pressure side of the system and entering the low pressure side through the orificed valve seat 63 becomes expanded (partly liquid and partly gas). The expanded refrigerant is received in the conduit 50 at pressures somewhat greater than those normally existing in the expansion conduits. This high pressure expanded refrigerant leaves the injector and enters the liquid refrigerant in the supply conduit 50 where the pressure is low. Consequently, the injector provides a means of positively circulating liquid refrigerant in the various refrigerant evaporators. It will also be noted that the gaseous part of injected refrigerant immediately initiates the ebullition of refrigerant in the expansion conduits upon its admission thereto. Also, the gaseous part of the injected refrigerant, in addition to starting the ebullition in the expansion conduits, promotes ebullition throughout its passage therethrough. By positively circulating, initiating and promoting ebullition and the circulation of refrigerant, both liquid and gaseous, in the refrigerant evaporators, the oil pumped thereinto by the compressor is readily returned to the compressor through the vapor conduit 82 by reason of its entrainment with the evaporated refrigerant.

In maintaining ice creams in a frozen condition, the user of the apparatus is frequently called upon to maintain different ice creams at different temperatures, such, for example, as bulk ice cream, small package ice cream and brick ice creams. Under these conditions, it has been found desirable and economical to operate the different expansion coils of the refrigerant low side at different temperatures suitable for refrigerating the different types of food articles.

In accordance with my invention, I provide for maintaining each of the evaporators either at the same temperature or for selectively varying the temperatures of each or all of said evaporators, depending upon the type of food articles to be stored. This is accomplished by merely providing manually operable valves 110 and 112 which are disposed in the extension conduits 55 and 54 of the refrigerant evaporators 44 and 43. The valves are for controlling the amount of refrigerant which is circulated through the evaporators 43 and 44. Preferably, these valves are of the well known packless type. The valves 110 and 112 are arranged so that the flow of refrigerant through expansion conduits 44 and 43 may be retarded to a predetermined amount or may entirely shut off. When the flow of refrigerant is entirely stopped through one of said conduits no refrigeration will take place in the respective expansion conduit. When the valve is operated to retard the flow of refrigerant through one of said evaporators, the refrigerating effect of said evaporator will be reduced and will be less than the evaporator which is provided with an unrestricted outlet passage. These valves are not of the pressure responsive type but are of the type which positively shut off the flow of refrigerant through an expansion coil or permit a predetermined amount to flow through said coil without variation, except when manually adjusted.

From the foregoing, it will readily be apparent that the retarding of the flow of refrigerant through some of the refrigerant evaporators will decrease the amount of liquid refrigerant as well as the amount of gaseous refrigerant which is being circulated through an evaporator. By slowing up the circulation of refrigerant through one of said evaporators and keeping the liquid level down, the rate of heat transfer has been lessened, which effects the heat transfer characteristics of the respective evaporator to thus maintain a higher temperature in said evaporator than in other evaporators in which the flow of refrigerant is unrestricted. It will also be noted that the refrigerant supply conduit is in open communication with the inlet ends of each of the refrigerant expansion coils, and for this reason the pressures in the various expansion coils will be substantially equal. Furthermore, it will be noted that the temperatures of the various evaporators may be selectively controlled by simply manipulating valves 110 and/or 112.

During the on-phase of the refrigerating cycle, the condensing element withdraws evaporated refrigerant from the gaseous refrigerant space in the header 34 and from the refrigerant expansion conduits 43, 44 and 45. During this time it has been found that there is a slight pressure difference equal to only a few inches of liquid refrigerant pressure on opposite sides of the valves 110 and 112 in conduits 55 and 54 when the valves are partly closed. This slight pressure difference causes a slight amount of liquid refrigerant in the expansion conduits 43 and 44 to be forced into the supply conduit 50 to other expansion conduits or into the refrigerant accumulator. During the off-phase of the refrigerating cycle and when the valves are but partly closed, it has been found, however, that the pressures on opposite sides of the valves are substantially, if not entirely, equal. Under these circumstances, the amount of liquid refrigerant in each of the expansion conduits is equal.

In order to arrange for the ready access of the valves 110 and 112, I have provided an opening 120 in the top wall of the cabinet, which is closed by removable cover or lid 122. This places the system in readiness for the selective control of temperatures in the different refrigerant evaporators.

In refrigerating systems of the type herein described wherein different temperatures are maintained in the different evaporators, it has been found desirable to provide means for preventing the transfer of heat from an evaporator maintained at a higher temperature to an evaporator operating at a lower temperature. For this purpose, I provide insulating material 125 between the different evaporators. Thus, the temperature of one evaporator can effect only to a slight extent the temperature of another.

In Figs. 5 and 6 there is shown a modified form of refrigerating apparatus which comprises, in general, an insulated cabinet 140 having a compartment 142. Within the compartment 142 there is disposed a primary refrigerant evaporator 145 and secondary refrigerant evaporators 147 and 148. The evaporators are each preferably formed of a single continuous conduit. The evaporators 145, 147 and 148 are wound around and in good thermal contact with sleeves 150, 151 and 152, respectively. Liquid refrigerant is supplied to and the gaseous refrigerant is withdrawn from the primary evaporator 145 in a like manner as refrigerant is supplied to and withdrawn from evaporator 45, shown in Fig. 1, which is, briefly, through a supply conduit 155 from the

refrigerant accumulator and from the injector (not shown), and the gaseous refrigerant is withdrawn into the refrigerant header through a vapor conduit 157. The primary system, in addition to the evaporator 145, supply conduit 155, vapor conduit 157, header and accumulator, also includes a cooling plate 160. The inlet of the plate 160 is connected to the supply conduit 155 by means of a conduit 162, and the outlet 10 of the plate 160 is connected to the vapor conduit 157 by conduit 164. The condensing element 30, shown in Fig. 1, may be used as part of the primary system.

Suitably secured to opposite sides of plate 160 15 are metal members 170 and 172 to provide chambers 174 and 175 for condensing evaporated refrigerant in the secondary systems. The secondary evaporator 148 is connected to chamber 174 by a liquid inlet conduit 176 and an outlet conduit 178. Secondary refrigerant evaporator 147 is connected to chamber 175 by a liquid inlet conduit 180 and a refrigerant return conduit 182. During operation of the apparatus, liquid refrigerant is evaporated in the evaporators 147 25 and 148 whence the evaporator refrigerant passes through conduits 182 and 178 to chambers 175 and 174, respectively, to be condensed. The condensed refrigerant is recirculated through conduits 180 and 176.

30 In order to control the temperatures in the secondary systems, I provide valves 185 and 186 which are disposed in conduits 178 and 182, respectively. These valves are preferably of the well known packless type like previously described and are employed to retard the flow of refrigerant through the secondary refrigerant evaporators to vary the heat transfer characteristics with respect to the primary evaporator and with each other. By this arrangement, the pressures in each of the secondary systems remain the same throughout each system. Furthermore, by the present arrangement it is possible to maintain three independent temperatures as is possible with the apparatus shown in Fig. 1 where 45 but one refrigerant is used.

Fig. 7 shows diagrammatically a modified form of refrigerating apparatus and comprises, in general, evaporators 190, 191 and 192. A common liquid refrigerant supply conduit 194 is connected 50 to each evaporator and in open communication therewith. At the outlet ends of the evaporators 190 and 191 are disposed valves 196 and 197, respectively. These valves are of the type which may be manually set to retard the flow of refrigerant through the evaporators 190 and 191 55 in varying amounts. To the valves 196 and 197 are connected thermostatic bulbs 200 and 201, respectively. These bulbs are filled with expandible fluids and are arranged to be responsive to 60 changes in temperatures of the evaporators 190 and 191 for varying automatically the amount of restriction offered by the valves 196 and 197. This arrangement may be advantageously used 65 in the event insulating material is not used between the different evaporators to compensate for the transfer of heat from one evaporator to another when one is operated at a higher temperature than the other. However, the thermostatic bulbs are not provided for intermittently 70 opening and closing the outlet passages of the evaporators but are merely for the purpose of cooperating for heat transfer to maintain substantially constant temperatures in each evaporator. This system may be connected to a refrigerant header, injector, accumulator and con-

densing element, the same as shown in Fig. 1. However, the operation of the motor-compressor unit of such condensing element may be controlled by means of a thermostatic bulb 130 which is responsive to changes in temperatures of evaporator 192 and which may be connected to the automatic switch 85.

Although only a preferred form of the invention has been illustrated, and that form described in detail, it will be apparent to those skilled in the art that various modifications may be made therein without departing from the spirit of the invention or from the scope of the appended claims.

What I claim as my invention is:

1. The method of refrigeration which consists in maintaining a temperature differential between a number of different refrigerant evaporators by maintaining therein substantially equal levels of liquid refrigerant during the off-phase 20 only of the refrigerating cycle and maintaining substantially different levels of liquid refrigerant in the different evaporators only during the on-phase of the refrigerating cycle.

2. Refrigerating apparatus comprising, in combination, a number of different refrigerant evaporators, a conduit in open communication with said evaporators, means for injecting expanded refrigerant into said conduit means for controlling the flow of refrigerant through said evaporators 30 and an outlet chamber in open communication with each evaporator whereby injected refrigerant or liquid refrigerant entrained with evaporated refrigerant is free to pass continuously through each evaporator at all times.

3. Refrigerating apparatus comprising, in combination, a cabinet, a plurality of open top sleeves disposed in said cabinet, a number of different refrigerant expansion conduits, one being wrapped around each of said sleeves, a liquid refrigerant 40 feed line common to each of said evaporators and in open communication therewith, outlet conduits for said evaporators and in open communication therewith, means for controlling the flow of refrigerant through at least one of said conduits and insulation between said evaporators to prevent the transfer of heat from one evaporator to another.

4. The method of refrigeration which consists in establishing a plurality of different refrigerant evaporating zones in open communication with each other at their inlets and outlets and passing injected refrigerant through said zones in varying amounts to maintain a temperature 55 differential between the different zones.

5. Refrigerating apparatus of the type wherein multiple temperatures are maintained, including a plurality of refrigerant evaporators, one of said evaporators having an outlet restricted to the 60 flow of refrigerant therethrough, means connecting the inlet of the evaporators in open communication with the outlet of the evaporators whereby refrigerant is free to pass at all times through said means and evaporators, said restricted portion maintaining the temperature of one of said evaporators above another evaporator of the apparatus, and means for injecting refrigerant into said apparatus.

6. A refrigerating system comprising a plurality of refrigerant evaporators interconnected in such a manner that refrigerant is free to pass continuously therethrough, means for injecting refrigerant into said evaporators, and means for restricting the passage of refrigerant through one 75

of said evaporators to maintain a temperature differential between said evaporators.

7. A refrigerating system including a plurality of flooded evaporators, a conduit connecting the lowermost portion of one of said evaporators to the others, means for supplying liquid refrigerant to said evaporators, means for withdrawing gase-

ous refrigerant from said evaporators, and means controlling the withdrawal of gaseous refrigerant from one of said evaporators for maintaining said one evaporator at a predetermined temperature higher than that of the others of said evaporators. 5

LAWRENCE A. PHILIPP.
